UNITED STATES PATENT OFFICE.

CHARLES H. CROWELL, OF SWAMPSCOTT, MASSACHUSETTS.

STAY-STRIP.

1,150,418.

Specification of Letters Patent. Patented Aug. 17, 1915.

Application filed January 27, 1913. Serial No. 744,308.

To all whom it may concern:

Be it known that I, CHARLES H. CROWELL, a citizen of the United States, residing at Swampscott, county of Essex, State of Massachusetts, have invented a certain new and useful Improvement in Stay-Strips, of which the following is a specification, reference being had therein to the accompanying drawings.

10 My invention relates to a prepared stay strip for application to box corners and the like, and it resides in a strip which has been folded upon itself and pressed in its folded position to fracture and break up the adhesive coating along the line of the fold and at the same time to take all resiliency along the line of fold out of the material of which the strip is composed. The purpose in thus preparing the stay strip is to insure 20 its even and uniform application to a box corner or the like when it is applied thereto, as by a corner staying machine, and also to insure its firmly adhering to the said corner.

Stay strip as now used in corner staying machines is frequently prepared by marking or indenting it along a central line for the purpose of causing it to be fed evenly onto the box corner. There are various methods of thus marking stay strip and some of 30 these are effective for this purpose. No stay strip is produced, however so far as known to me, which is not only effectively marked but which also has had all the resiliency removed along the line of fold. By resiliency is meant the tendency which the strip has when folded over the corner to lift off and return to or assume its flat condition. One of the largest uses of corner stay strip is its application to box corners by means 40 of a corner staying machine. In this case the gummed stay strip is moistened as it is fed forward through the machine just prior to its being placed on the corner of a box; and it is then subjected when in position to 45 momentary pressure between a fixed die and a movable die in the manner well known to those skilled in the art. A stay strip, the adhesive surface of which is subjected for only a very brief time to moisture and which

50 is then applied to a box corner and given merely a moment of pressure to force it into contact with the box corner, will lift away from the box corner by reason of its resiliency before the adhesive has had an opportunity to secure it in place.

The object of my invention is a prepared

stay strip to avoid the objections above noted.

The invention will be fully understood from the following description taken in connection with the accompanying drawings, and the novel features thereof are pointed out and clearly defined in the claim at the close of this specification.

In the drawings, Figure 1 is a view in perspective of a roll of stay strip from which my improved stay strip is made. Fig. 2 is a view in perspective of a section of stay strip in folded position. Fig. 3 is a view in perspective of a roll of my improved stay strip.

Referring to the drawings A designates a roll of flat stay strip made in the well known manner from paper, cloth or the like, and preferably having one surface thereof 75 gummed. The flat strip designated B is folded upon itself as shown in Fig. 2, bringing the edges together, and so that the two faces 1 and 2 of the strip are in contact. Thus folded the strip is subjected to pressure and especially along the line of fold C. This 80 fractures the adhesive coating along said line, as also any sizing or the like which may be in the material of which the strip is composed. The strip is then flattened out 85 by unfolding it and may be rewound into a roll and is ready for use. If one folding and pressing operation is not sufficient to remove all resiliency from the line of fold the strip may be reversely folded and again 90 pressed, and in the case of a strip made from very intractable material it may be again reversely folded and subjected to a third pressing, the object being to take away all stiffness from the line of fold so that 95 the material along that line will be limp and when the strip is placed on a box corner the two halves will be simply hinged together but with no tendency whatever to revert to a flat condition, that is to come into 100 the same plane.

A stay strip thus prepared may be rewound into a roll, kept for an indefinite period and when used will feed evenly onto a box corner and although coated with a 105 quick moistening adhesive having a minimum of adhesive quality, may be securely applied to the corner of a box or the like by being subjected to a single pressure of the pressing die in the stay machine.

What I claim is:

The improved stay strip comprising a

strip of gummed tape having a median bending line, the gum along said median bending line being fractured and the tape along said line being rendered pliable to
5 form a bending line from which the natural resiliency has been removed.

In testimony whereof I affix my signature,
in presence of two witnesses.

CHARLES H. CROWELL.
